UNITED STATES PATENT OFFICE.

GAUDENZ BÄYER AND CARL HOCHHERZ, OF AUGSBURG, GERMANY, ASSIGNORS TO THE FIRM GEBRÜDER BAYER, OF AUGSBURG, GERMANY.

REFRIGERATING APPARATUS.

Application filed December 19, 1923. Serial No. 681,526.

To all whom it may concern:

Be it known that we, GAUDENZ BÄYER and CARL HOCHHERZ, both citizens of the German Republic, and residents of Augsburg, 5 Bavaria, Germany, have invented certain new and useful Improvements in Refrigerating Apparatus, of which the following is a specification.

Our invention relates to refrigerating apparatus, more particularly of the absorption type of refrigerating apparatus, and has for its main object the abolishment of check valves, expansion valves and, in general, of all moving parts which are liable to get out 10 of order, which complicate the arrangement and require skilled attendance.

In an apparatus according to our invention these draw-backs are entirely absent, and in a preferred form of the invention we 15 connect the still-absorber and the evaporator through the condenser, so that the ammonia gas or the like refrigerating agent, after having been developed in the still-absorber, may flow into the condenser in order to be 20 liquefied and to thence flow into the evaporator, from which it passes back into the still-absorber after evaporation. It is one 25 of the objects of the invention to improve the connection between condenser and evaporator in so far as to enable the formation of 30 a liquid seal by means of the liquefied refrigerating agent, which seal would act as a valve and prevent the gas taking its way 35 from the evaporator into the condenser during the absorption period.

The said liquid seal also renders it possible, without the necessity of check valves, to 40 convey the liquid contents of the evaporator, and thus any water which may be contained 45 therein, into the still-absorber, and it is a further object of our invention to provide simple and efficient means whereby such 50 conveyance of the liquid may be carried out whenever desired.

45 In the accompanying drawing:

Fig. 1 is a diagrammatic sectional view of an apparatus constructed in accordance with our invention,

50 Fig. 2 is a detail, also diagrammatic, of a modified form of our invention and shows a different arrangement for the formation of the liquid seal,

55 Figs. 3 and 4 are two further modifications of the apparatus, likewise in diagrammatic sectional view, in which means are

provided to enable the return of the liquid from the evaporator into the still-absorber at will.

Referring to Fig. 1, α is the still-absorber resembling a kind of boiler and which may be heated for example by means of the electric heating elements δ . The usual cooling device for the still-absorber which comes into operation during the absorption process is denoted by c . A tube d leads from the top of the boiler to the condenser e which latter is connected to the lower portion of the evaporator f by a tube g , so that a liquid seal will be formed in this connection member. In the example of Fig. 1 this is rendered possible by the provision of a loop h in the tube g , terminating closely above the bottom of the evaporator f so as to have its opening permanently submerged in the liquid. From the top of the evaporator a conduit i leads upwardly into the still-absorber α and terminates into a distributor k below the liquid level in the said vessel.

Fig. 2 shows the vital parts of a modified arrangement for the formation of a liquid seal between condenser and evaporator. In this modification the discharge pipe g of the condenser terminates into a liquid trap l which preferably is arranged within the cooling range of the evaporator f , or of the refrigerating plant respectively, so as to open into the evaporator. The trap remains permanently filled with the liquefied refrigerating medium, which does not evaporate 90 there.

The arrangement according to the invention operates in the following manner: The gases which emanate from the still-absorber during the boiling process pass into the condenser e where they are caused to condense and collect primarily within the liquid recipient h , or l respectively, arranged between condenser and evaporator, after which they enter the evaporator. For the whole duration of evaporation and absorption there will always remain a liquid seal in the connection between condenser and evaporator, which liquid seal exerts a stronger resistance than the resistance likely to be caused by the liquid contents in the still-absorber. In this way all valves or equivalent elements may be successfully abolished. The gases which do not find a passage in the direction of the condenser are only able to pass from 110

the evaporator through tube *i* into the absorber.

However, even if a water separator were provided in such an arrangement, experience has shown that water would yet enter the evaporator in course of time and thus affect its efficiency. It is therefore necessary to remove all liquid contents of the evaporator, including any water which may have collected therein, and to return same to the still-absorber. In a plant according to the invention this may be accomplished, owing to the provision of the liquid seal, simply by the arrangement of special conduits.

Two examples of such an arrangement are diagrammatically shown in Figs. 3 and 4 of the drawings. In both these figures the general arrangement of the apparatus corresponds to that shown in Figs. 1 and 2, in which a liquid seal is formed in the connection between the condenser *e* and the evaporator *f*.

In the arrangement shown in Fig. 3 the top of the evaporator *f* is connected to the still-absorber *a* by means of a tube *i* as in the example shown in Fig. 1. Apart from the said tube another conduit *m* is provided which reaches down to the bottom of the evaporator and serves to return water from the evaporator to the still absorber. It will be seen that the clear diameter of tube *i* is so narrow, as compared with that of the tube *m*, that the difference of pressure between the evaporator *f* and the absorber *a* during the absorption period will normally just be sufficient to allow of the vapours passing through the said tube *i*, while it will not be sufficient to force the liquid through the tube *m*, since the column of liquid contained therein would be too heavy to be lifted by the normal working pressure. However, by artificially increasing the difference of pressure between the evaporator and the absorber, gas will suddenly develop in such large quantities that the increase in pressure can no longer be compensated through the narrower tube *i*, with the result, that the liquid contents of the evaporator *f* will be precipitated from the evaporator along the path of least resistance, namely through the pipe *m* into the still-absorber *a*. Such artificial increase of pressure may be obtained either by the application of a particularly effective cooling to the coil *c* within the still absorber *a*, or by the application of heat to the evaporator. Since the tube *m* is arranged to dip right down to the bottom of the evaporator *f* any water collected therein will be forced up the said tube, which evidently is the purpose of the arrangement, whilst at the same time the provision of the liquid seal in the connection pipe *g* prevents the liquid from taking its way through the condenser *e*. For the purpose of the proper working of the apparatus it is advisable to

make the cross section of the tube *g* so narrow, or to provide corresponding obstructions or restrictions in its clear diameter, as to afford a considerable resistance to the passage of the liquid into the condenser which, however, would not hinder the slow trickling down process of the liquefied refrigerating medium from the condenser into the evaporator.

In order to artificially increase the difference in the pressure between evaporator and absorber, means may be provided in the former to enable hot water being filled in, such means, for example, as the cup *n* shown in Figs. 3 and 4. Such cups are sometimes used in the smaller type of refrigerating apparatus for the purpose of making ice and they may now be used for occasionally effecting an increase in the gas pressure. If, as mentioned before, the cross sections of the conduits *i* and *m* are compensated by a certain restriction at the entrance of tube *i* within the evaporator *f* then the tube *m* may be joined to the tube *i* at any place of the latter above the said entrance. In Fig. 3 this is indicated by the broken lines at the top of the figure.

In the modification of Fig. 4 a single connection *i* only is shown between the evaporator and the absorber, similar to that shown in Fig. 1, but with the difference, that this tube *i* has an extension *o* which dips down as far as to the bottom of the evaporator. Above the normal liquid level and within the evaporator *f* a small opening *p* is provided in the tube *i*—*o* which, under normal working pressure, is sufficient to permit the passage of the gas into the absorber. However, the clear diameter of the opening *p* in the tube *i*—*o* is not large enough to pass such large volumes of gas as would be spontaneously developed by an artificial increase of pressure and, therefore, the gas in this case would press upon the liquid contents in the evaporator and precipitate same through the extension *o* and the tube *i* into the absorber. It will be evident, that owing to the liquid seal in the conduits *g*, *h* and the resistance offered by the narrow cross sections of these conduits, such artificial pressure increase will not be able to take its way through the condenser *e* to any appreciable extent.

It will also be evident that during the evaporation period the liquid standing in the main chamber *f*, and in the lower portion of the pipe *g*, will have a comparatively large area of liquid exposed for evaporation in the chamber, and only a small area of liquid exposed for evaporation through the pipe *g* and the condenser.

What we claim is:—

1. In a refrigerating apparatus of the absorption type a still-absorber, a condenser and an evaporator, the condenser connecting

- the still-absorber with the evaporator, means in the connection between condenser and evaporator adapted to collect the liquefied refrigerating medium and to thus form a liquid seal, a directly communicating tube conduit between still-absorber and evaporator emanating from the still-absorber below the liquid level of same and passing through the evaporator so as to terminate 10 at the bottom of same, and an orifice in the wall of the said tube within the evaporator and above its liquid level, and having a diameter smaller than that of the tube conduit.
- 15 2. A refrigerating apparatus of the absorption type, including a still-absorber, an evaporator, a connecting means for the flow of refrigerant from the still-absorber to the evaporator, and including a condenser, 20 and separate connecting means for the return of refrigerant from the evaporator to the still-absorber, and having a comparatively small port at the upper part of the evaporator for the normal flow of vaporized refrigerant during the cooling period and a larger port at the lower part of the evaporator for the flow of liquid upon abnormal heating, high rate of evaporation, and high pressure in the evaporator.
- 25 3. A refrigerating apparatus of the intermittently acting absorption type comprising a single fluid circulating circuit including a still-absorber, an evaporator, connecting means for the flow of refrigerant from the evaporator to the still-absorber, and having a permanently open gas port at the upper part of the evaporator and a permanently open liquid port at the lower part of the evaporator, and separate connecting means for the flow of refrigerant 30 from the upper part of the still-absorber to the evaporator, said last mentioned means including a condenser and a liquid seal.
4. A refrigerating apparatus of the intermittently acting absorption type, comprising a single valveless and permanently open fluid circulating circuit including a still-absorber, an evaporator including a chamber adapted to receive the main body 45 of liquefied refrigerant from the condenser during the heating period, and exposing a comparatively large area of said refrigerant for evaporation during the cooling period, connecting means for the flow of gas from the upper part of the evaporator to the lower part of the still-absorber, and connecting means for the flow of gas from the upper part of the still-absorber to the evaporator, said last mentioned means including a condenser, and means beyond the 50 condenser in the direction of the flow of the gas for maintaining a small body of liquid with a very small surface area exposed in said connecting means, whereby
- only the gas resulting from evaporation at 55 said surface will return through said condenser to the still-absorber.
5. A refrigerating apparatus of the intermittently acting absorption type, comprising a single valveless and permanently open fluid circulating circuit including a still-absorber, an evaporator including a chamber adapted to receive the main body of refrigerant during the heating period, connecting means for the flow of gas from the upper part of the evaporator to the lower part of the still-absorber and connecting means for the flow of gas from the upper part of the still-absorber to the evaporator, said last mentioned means including a condenser, and being adapted beyond said condenser to retain a small quantity of the liquefied refrigerating medium and to thus form a liquid seal preventing return flow of evaporated refrigerant from the 75 evaporator through the condenser to the still-absorber.
6. A refrigerating apparatus of the intermittently acting absorption type, including a still absorber, an evaporator, a condenser arranged in circuit between the still-absorber and the evaporator, and valveless permanently open communication means between the evaporator and the still-absorber, and having a small outlet from the upper part of the evaporator and an outlet from the lower part of the evaporator, the relative areas of said outlets being such that the first mentioned outlet permits the free escape of gas during normal cooling operation, but permits the development of pressure in the evaporator and the forcing of liquid through said second mentioned outlet upon abnormal high rate of evaporation 100 in the evaporator.
7. A refrigerating apparatus of the intermittently acting absorption type, including a still-absorber, an evaporator, valveless, permanently open communication means between the evaporator and the still-absorber, and having an outlet from the upper part of the evaporator and an outlet from the lower part of the evaporator, the relative areas of said outlets being such that the first mentioned outlet permits the free escape of gas during normal cooling operation, but permits the development of pressure in the evaporator and the forcing of liquid through said second mentioned outlet upon abnormal high rate of evaporation in 110 the evaporation, and a second communication means between the still absorber and the evaporator, and including a condenser and a liquid seal.
- In testimony whereof we affix our signatures.

GAUDENZ BÄYER.
CARL HOCHHERZ.
